Donald L. Maxson

Attorney

UNITED STATES PATENT OFFICE.

MATTHEW J. ROONEY, OF BLOOMFIELD, NEW JERSEY.

COMB-CLEANER.

1,384,152.

Specification of Letters Patent. Patented July 12, 1921.

Application filed January 21, 1921. Serial No. 438,897.

To all whom it may concern:

Be it known that I, MATTHEW J. ROONEY, a citizen of the United States, residing at Bloomfield, in the county of Essex and State 5 of New Jersey, have invented certain new and useful Improvements in Comb-Cleaners, of which the following is a specification.

This invention relates to comb cleaning devices, and more particularly to that type 10 of cleaner which will employ the use of any kind of cloth or like material for cleaning between the teeth of the comb.

An object of the invention is to provide a comb cleaning device of integral construction, which will be efficient in use and inexpensive to manufacture.

A further object is to provide a comb cleaning implement, which will be provided with suitable means for clamping the cleaning cloth or material firmly at one end, and with a suitable gripping means at its opposite end.

Other objects will appear as the description proceeds.

25 In the accompanying drawings which constitute a part of my application,

Figure 1 is a perspective view of my improved comb cleaning device, showing the relative position of the operator's hands 30 when the cleaner is in use, and

Fig. 2 is a side elevation of the improved comb cleaning implement.

Like characters of reference are used throughout the following specification to 35 designate corresponding parts.

The comb cleaner 1 is made more or less in the shape of a hack saw frame, and is provided at its outer end with a plurality of gripping teeth 2.

40 Adjacent the end of the frame carrying the teeth 2, is a slot 3, which extends a considerable distance into the frame, and runs parallel with said teeth. The opening of this slot 3, is formed with rounded corners 45 4, to more easily facilitate the placing of the cleaning cloth or material 5 in position within said slot.

At the opposite end of the frame 1, there is a right angular bend made, as at 6, and 50 then a second bend 7, which extends parallel to the frame 1. This angular formation constitutes a gripping or handle portion for the person operating the cleaner.

A portion of the back of the frame 1, is 55 serrated to form the teeth 8, which may be used to advantage in many respects, as for

example to shave off some shaving soap into a shaving cup.

An opening 9 is provided in the handle or gripping end of the frame, whereby the 60 cleaner may be placed or hung over a nail when not in use.

The operation of this improved comb cleaner is as follows: A piece of cloth or rag is placed into the slot 3, after which it 65 is bent under the frame toward the teeth 2, then up and over the same, and the free end of the cloth is then placed between the second and third fingers, and pulled tight to a position just under and adjacent the handle 70 portion of the frame 1, as shown in Fig. 1 of the drawings. It will be found that by placing the frame on the first finger, and exerting a pressure partly on the portions 6 and 7 by means of the thumb as shown in 75 the drawings, that the cloth will be held in a firm manner.

One of the main features of this cleaner is, that it will just as thoroughly clean a fine tooth comb as a comb having the largest 80 teeth. This is made possible by having the slot so that the cloth may be single, doubled or folded over as many times as desired. It will therefore be seen that if the cloth were single or even doubled, that a fine tooth 85 comb might be cleaned. Likewise, if a large comb were to be cleaned, the cloth could be folded over several times, thereby making it a corresponding thickness as the distance between the largest teeth. 90

It will be readily understood that the principle involving the cleaning of a comb with a piece of cloth or similar material is the only practical way, since were strands used, they would get crossed, and finally 95 break the teeth, also they would not entirely fill up the space between the teeth, and therefore not thoroughly clean the comb.

With my improved cleaner, I provide an integral structure that is easy to manipulate, and inexpensive to manufacture, and one which will successfully and efficiently clean any type of comb, whether small or large.

It will also be seen that with this cleaner, 105 I am enabled to clean between the teeth of barber's clippers and even the most delicate machinery, as there will be no snapping of threads to become entangled in the mechanism.

While I have described this implement as primarily a comb cleaner, I do not intend to 110

limit myself, as many minor changes in detail of construction may be resorted to without departure from the spirit of the invention.

5 Having thus described my invention what I claim as new, and desire to secure by Letters Patent of the United States is:—

10 1. A comb cleaner comprising an integral construction, a toothed gripping portion at one end of said construction, said gripping portion being provided with a slot adjacent thereto to receive the cleaning medium, and a handle portion at the opposite end of said construction.

15 2. A comb cleaner comprising an integral construction, a toothed gripping portion at one end of said construction, said gripping portion being provided with a wedging slot parallel with and adjacent thereto to receive the cleaning medium, and angularly disposed means at the opposite end of said construction to form a handle portion.

3. A comb cleaner comprising an integral construction, a toothed gripping portion at one end of said construction, said gripping portion being provided with a wedging slot parallel with and adjacent thereto to receive the cleaning medium, angularly disposed gripping means at the opposite end of said construction, and said gripping means being provided with an opening, whereby said cleaner may be attached to any suitable object. 25 30

4. A comb cleaner comprising an integral frame, a toothed gripping portion at one end of said frame, said gripping portion being provided with a slot parallel with and adjacent thereto, the ends of said slot being flared to more readily receive the cleaning medium, and an angularly disposed handle portion at the opposite end of said frame. 35 40

In testimony whereof I affix my signature.

MATTHEW J. ROONEY.
